UNITED STATES PATENT OFFICE.

SIMON COOPER, OF BROOKLYN, NEW YORK, ASSIGNOR TO PINE HILL CRYSTAL SPRING WATER COMPANY, OF NEW YORK, N. Y., A CORPORATION OF NEW JERSEY.

METHOD OF DISPENSING LIQUIDS.

1,319,377.

Specification of Letters Patent.

Patented Oct. 21, 1919.

Original application filed December 2, 1915, Serial No. 64,633. Divided and this application filed October 24, 1917, Serial No. 198,206. Renewed April 4, 1919. Serial No. 287,633.

To all whom it may concern:

Be it known that I, SIMON COOPER, a citizen of the United States, residing at Brooklyn, in the county of Kings, and State of New York, have invented certain new and useful Improvements in Methods of Dispensing Liquids, of which the following is a specification.

This invention relates to a method of dispensing liquids and some features of the invention render it particularly applicable to a type of water cooler in which the water or other liquid is held in an inverted receptacle. In such a cooler, as the liquid 10 is drawn off from time to time the air space or air chamber in the upper part of the receptacle increases in volume and the air which passes into the receptacle, drawn as it is from the air in the room or hall where 15 the cooler stands, may contain impurities or bacilli noxious to human life. This disadvantage is aggravated under some circumstances for the reason that frequently the receptacle is of such a large size that 20 considerable time elapses before the liquid is entirely consumed. During all this time the surface of the liquid is exposed to the air in the air chamber and the receptacle which is generally of glass may be placed 25 in the sunlight, producing conditions which are highly favorable to the propagation of bacilli or bacteria. Furthermore, such apparatus is often constructed in such a way 30 that the exterior of the mouth of the receptacle comes in direct contact with the water, or other liquid which is to be drunk. Such an apparatus as this described is evidently very unsanitary.

Among the objects of my invention is to 35 provide a dispensing method which may be practised with a very simple dispensing apparatus which will be sanitary and which will operate in a very simple manner to permit the liquid to be drawn off as may be 40 desired, and further to provide for sealing the liquid so that where air must come in contact with it, this air will be purified. I effect this result in a very simple manner and without the necessity of the use of 45 valves having moving parts, except the usual faucet or other means for drawing off the liquid; and in order to carry out my purpose more completely the apparatus is preferably constructed so as to prevent any pos-

sibility of the liquid which is to be drunk, 55 from coming in direct contact with the exterior of the mouth of the receptacle. In addition to this it is my object to provide improved means for effecting the cooling of the liquid before it is consumed. 60

My invention includes the method by which I accomplish the general purposes of my invention.

In the drawings, in which is shown a form of apparatus for carrying out my invention, Figure 1 is a central vertical section partly in elevation taken on the line 1—1 of Fig. 2; Fig. 2 is a plan view with certain parts removed; Fig. 3 is a central vertical section taken on the line 3—3 of Fig. 2. 70

The apparatus may comprise a refrigerating compartment 1 formed within a case 2 having double walls 3 which may be packed with a suitable heat non-conducting packing 4. The case 1 may have two removable cover sections 5 and 6 which are of semi-circular form so as to form a suitable cover or lid for the case 1 which is represented for example, as of circular form. The cover section 5 may have a handle 7 rendering it 80 easily removable to give access to the interior which may receive a refrigerating substance such as ice, indicated at 8; and the interior of the refrigerating compartment preferably has an overflow tube 9 with a removable stopper or closure 9^a. By removing the plug 10^a at the bottom of the case the refrigerating compartment may be completely drained through the outlet 10. 85

The cover section 6 is preferably constructed to support an inverted receptacle such as the receptacle or large bottle 11, and the parts are so arranged as to prevent contact of the liquid within the bottle and the exterior of the mouth of the bottle before the liquid is consumed. In order to accomplish this the cover section 6 is preferably provided with a funnel-shaped depression 13 supported on a housing 12 and this housing has an upwardly extending closure or plug 19 which fits into and will seal the mouth of the receptacle or vessel. The plug has a liquid duct 14 which extends downwardly through the same and an independent air inlet or duct 15 composed of two 100 branches 15^a and 15^b. I provide means for effecting a hydrostatic seal for normally preventing the liquid from flowing out from

the receptacle and for normally preventing air from leaking through the air duct 15, and into the air chamber 11^a in which a partial vacuum exists above the liquid level indicated by the line 11^b of the receptacle. I also construct the parts so as to prevent the exterior of the mouth of the receptacle from touching the liquid. To accomplish this I provide a delivery chamber 23 to receive liquid from the receptacle through the duct 14 and to contain a hydrostatic sealing bath, the level of which is normally maintained at about the position of the dotted line 230, see Fig. 1. This delivery chamber 15 preferably has an extension 22 which projects toward the front of the cooler and is provided with a delivery pipe 27 which may have means such as a faucet 28 for drawing off the liquid from the delivery chamber. The delivery chamber is preferably elevated by means of cleats 24 above the bottom of the refrigerating compartment so that the refrigerating water will pass or circulate on all lateral sides of and 20 on the under side of the delivery chamber. This gives a very good cooling effect.

The lower portion of the housing 12 seats 30 on a gasket 26 on a cover 25 of the delivery chamber 23 so as to form a substantially air-tight connection and prevent the entrance of air to the air chamber in which air is confined above the level of the liquid in the delivery chamber 23. The receptacle is inverted and put in place, and then the liquid 35 flows down the duct 14 and partially fills the delivery chamber 23, normally mounting to and maintaining a level therein at about the point indicated by the line 230, which is sufficiently above the lower end of the duct 40 to produce equilibrium in the liquid columns in the delivery chamber and in the receptacle 11.

When a condition of equilibrium exists, the liquid in the chamber 23 at about the 45 level indicated by the line 230, forms a liquid supply column which, together with the atmospheric pressure upon its upper surface, forms a counterbalancing column for counterbalancing the column of liquid in the duct 14, the receptacle 11 and the air in the air chamber 11^a.

And, likewise, during this condition of equilibrium, liquid stands in the branches 50 15^a and 15^b of the air duct, so that the liquid column in the branch 15^b together with the atmospheric pressure upon its upper surface forms a counterbalancing column to counterbalance the column of liquid in the duct 15^a, the receptacle 11 and the air in the 55 air chamber 11^a.

When a quantity of liquid is withdrawn at the faucet 28 the level of the sealing bath in the delivery chamber 23 will drop to a lower level such as indicated by the line 231. 60 This reduces the liquid column in the chamber 23 and disturbs the equilibrium. The

first effect of this is to break the seal which is formed in the air duct, and causes the admission of air to the interior of the receptacle 11. This effect is the first effect produced on account of the fact that the column of liquid in the duct 15^a and the receptacle is shorter than the column of liquid in the duct 14 and the receptacle. The next effect is a downward flow of liquid through the 70 duct 14 into the chamber 23, and this downward flow will continue until the faucet 28 is closed and equilibrium of the liquid columns is reestablished.

No air passes up the duct 14 to the liquid 80 supply column.

This admitted air is preferably purified by passing it through a purifier, or filter 20 which may contain a removable wad 20' of absorbent material preferably held in place 85 by a baffle-form closure 21 through which the air may pass in. This admitted air is preferably taken from the interior of the refrigerating compartment, and I prefer to provide an air duct 16 for leading a portion 90 of the purified air to the air chamber in the delivery chamber 23 (from which all other air is excluded) in the upper portion of which air is confined above the sealing bath.

Any liquid spilled in placing the receptacle 95 11 in position drains through a duct 18 into the refrigerating compartment.

As the cover section 5 does not make an air-tight closure for the refrigerating compartment, the air ducts 15 and 16 are in communication with the atmosphere, but by utilizing the air from the interior of the refrigerating compartment to replace the volume of liquid withdrawn from receptacle 11, the admitted air in the receptacle will have been 100 refrigerated; and furthermore this cool air exerts a cooling effect on the liquid as it bubbles up through it. This bubbling up of the air will continue until equilibrium of the 105 hydrostatic columns occurs.

The ice 8 is preferably supported upon a removable grid 30 having bent cross bars 31, forming legs and having upwardly extending loops 30' for retaining the ice.

The receptacle 11 may be conveniently 110 held in a rudimentary crib formed of fixed standards 32 and 33, and a movable standard 34 which may be pivoted to permit its being swung out of the way when the receptacle is being put in place. And a latch 36 115 may be provided for holding the movable standard in its holding position.

By reason of the fact that the air duct is effectually sealed by the liquid itself, this air duct may be made large enough to admit 120 the air in such quantity as to cause a very uniform outward flow of the liquid. The trap formed by the two tubes 15^a and 15^b is an important part of the invention, and the 125 hydrostatic seal contained therein is con- 130

trolled by the relation between the supply column in the bottle and the delivery column 23. When these two columns are in equilibrium, there is a seal in the trap, but as soon as this equilibrium is disturbed by the drawing off of water from the delivery column the consequent increased vacuum in the space 11^a causes air to pass in through the tube 15^b, displacing the water in the trap, which backs up into the bottle, and the necessary quantity of air then passes on through the bottle into this space 11^a, to restore a condition of equilibrium between the vacuum and the atmospheric pressure. The path of the air through the tubes 15^b and 15^a is the shortest path, and consequently there is no tendency for the air to pass through the delivery column 23 and thence up through the tube 14.

It is understood that the embodiment of the invention set forth herein is only one of the many embodiments or forms the invention may take, and I do not wish to be limited in the practice of my invention nor in my claims to the particular embodiment set forth.

The present application is a division of my prior Patent 1,236,912, filed December 2nd, 1915, Serial No. 64,633 for liquid dispensing apparatus.

I claim:

1. The method of dispensing a liquid which consists in maintaining a liquid-supply column with a partial vacuum above the same, maintaining a counterbalancing column of the liquid to counterbalance the supply column, maintaining an independent air inlet for admitting air through said supply column to pass into said partial vacuum,

and drawing off liquid from said counterbalancing column and thereby causing an inward flow of air in the air inlet and an outward flow of liquid from the supply column to the balancing column.

2. The method of dispensing a liquid which consists in maintaining a liquid-supply column with a partial vacuum above the same, maintaining a counterbalancing column of the liquid to counterbalance the supply column, maintaining an independent air inlet for admitting air through said supply column to pass into said partial vacuum, drawing off liquid from said balancing column and thereby causing an inward flow of air in the air duct and an outward flow of liquid from the supply column to the balancing column, and purifying the admitted air before admission through said air duct.

3. The method of dispensing a liquid which consists in maintaining a liquid-supply column with a partial vacuum above the same, confining a counterbalancing column of the liquid and air at atmospheric pressure to counterbalance the said supply column and form a hydrostatic seal therefor, maintaining an independent hydrostatically sealed air inlet to said liquid-supply column, drawing off liquid from said counterbalancing column and thereby causing an inward flow of air through said inlet, and an outward flow of liquid from said supply column to said counterbalancing column, admitting air to said confined air, and purifying the air admitted to the confined air and to the supply column.

In testimony whereof I affix my signature.

SIMON COOPER.
